COMBINATION CATALYTIC AND THERMAL CRACKING

Filed Dec. 23, 1942

UNITED STATES PATENT OFFICE

2,335,551

COMBINATION CATALYTIC AND THERMAL CRACKING

Richard F. Trow, Lawrenceville, Ill., assignor to
The Texas Company, New York, N. Y., a corporation of Delaware

Application December 23, 1942, Serial No. 469,913

6 Claims. (Cl. 196—49)

This invention relates to a combination catalytic and thermal cracking process and is concerned particularly with the processing of crude petroleum stocks to obtain maximum yields of high anti-knock motor fuel.

In accordance with the invention straight-run stocks, such as gas oil, are combined with intermediate stocks from the thermal cracking step and the mixture subjected to catalytic cracking while crude oil residual stocks, such as topped or reduced crude, and the higher boiling products from the catalytic cracking step are subjected to thermal cracking. In the processing of the gas oil or intermediate stocks straight-run gas oil and thermally cracked gas oil are subjected to single-pass catalytic cracking and the gas oil or higher boiling stock from the catalytic cracking operation, is subjected to single-pass thermal cracking. The relationship of the thermal and catalytic gas oil cracking steps is such that the thermal cracking serves to produce a stock well adapted for catalytic cracking and the catalytic cracking functions to produce a stock well adapted for thermal cracking. And by maintaining single-pass conditions in the catalytic cracking and thermal cracking operations respectively it is possible in each cracking stage to carry on a maximum extent of cracking which is conducive to conversion into gasoline constituents of high anti-knock quality.

For the purpose of fully disclosing the invention reference is made to the accompanying drawing which is a flow diagram illustrative of the invention.

Crude petroleum is directed by a pump 10 through a heat exchanger 11 wherein the crude oil is heated to the desired distilling temperature and passes thence to a distilling and fractionating tower 12. The heat exchanger 11 may be supplied with hot products from the cracking system. In the tower 12 vapors separate from residue and the vapors are subjected to fractionation to segregate the fractions desired. In the specific embodiment illustrated intermediate constituents, such as gas oil fractions, collect as a reflux condensate in a tray 13, heavy naphtha fractions collect in tray 14, while uncondensed vapors pass through a condenser coil 15 thence to a receiving drum 16 wherein a gasoline distillate is collected.

The thermal cracking portion of the system includes a heating coil 17 disposed in a furnace 18 and a heating coil 19 disposed in a furnace 20. A transfer line 21 from the heating coil 17 and a transfer line 22 from the heating coil 19

are merged to commingle the effluent from the two heating coils in a subsequent reaction zone for further thermal cracking. This reaction zone may include one or more reaction chambers. As illustrated, the products from heating coils 17 and 19 are merged for cracking in a reaction chamber 23, the effluent from which passes to a subsequent reaction chamber 24, the effluent from which passes to a final reaction chamber 25 wherein separation of vapors from liquid residue takes place. The several reaction chambers are insulated against heat loss so that each of the chambers may be maintained at a cracking temperature. Liquid is prevented from accumulating in any of the reaction chambers, the mixed liquid and vaporous and gaseous constituents flowing from chamber 23 through chamber 24 thence to chamber 25 where liquid constituents are separated from vapors and gases, the separated vapors passing through a vapor line 26 to a primary fractionating tower 27 and vapors uncondensed therein pass through a vapor line 28 to a secondary fractionating tower 29. Uncondensed vapors pass from the tower 29 through a condenser 30 thence to a distillate receiver or gas separator 31 wherein the gasoline or naphtha distillate is collected.

The thermal cracking portion of the system advantageously includes a heating coil 32 disposed in a furnace 33 and a heating coil 34 disposed in a furnace 35. These heating coils are intended particularly for the thermal cracking or reforming of light stocks, such as naphtha, as is explained hereinafter. The effluent from these coils, instead of being directed to the primary reaction chamber 23, is advantageously passed to a subsequent portion of the cracking zone or to the fractionating portion of the thermal cracking system. As illustrated a transfer line 36 from heating coil 32 and a transfer line 37 from heating coil 34 serve to direct the effluent from these coils to the primary fractionator 27.

The liquid residue separated in the reaction chamber 25 passes through a line 38 and pressure-reducing valve 39 to a coking drum 40. In practice a plurality of coking drums are employed so as to enable the removal of the coke without interrupting the continuity of the complete process. The coking drums are insulated against heat loss and a sufficient portion of the vapors from reaction chamber 25 is included with the liquid residue passed to the coking drum to accomplish autogenous coking therein. The evolved vapors from the coking drum pass

through a line 41 to a fractionating tower 42. This tower is formed with a primary dephlegmating section 42A which receives the vapors from the coking drum and a secondary section 42B separated by a trapout tray 43. In some cases an additional fractionating section 42C is provided separated from the section 42B by a trapout tray 44. Uncondensed vapors pass from the tower 42 to a condenser 45 thence to a distillate receiver or gas separator 46.

The catalytic cracking portion of the system includes a heating coil 47 disposed in a furnace 48 and a catalyst chamber 49 which receives the effluent from the heating coil and wherein the heated oil is contacted with a catalyst. The catalyst consists advantageously of a synthetic silica-alumina type of catalyst. Various acid-treated and metal-substituted clays such as the Super-Filtrols and acid-treated and metal-substituted natural or artificial zeolites, such as the artificial zeolite known as Doucile may be employed. Various metals such as uranium, molybdenum, manganese, lead, zinc, zirconium, nickel and the like, may be substituted in the clays or zeolites. Likewise, the combination of certain acid-treated active clays of the character of Filtral, together with added proportions of alumina or silica or both may be employed. Alumina alone may be used under certain conditions. The synthetic alumina catalysts can be improved by the addition of other constituents such as zirconium oxide or molybdenum oxide. The oil may be contacted with the catalyst in various ways. Thus the oil may be vaporized in the heating coil and the vapors passed through the reaction chamber provided with a stationary bed of the catalyst through which the vapors pass; or a moving mass of granular catalyst may be maintained in the reaction chamber; or finely divided catalytic material may be admixed with the oil stream prior to introduction to the reaction chamber; or the catalyst may be introduced in a finely divided, comminuted or powdered form suspended in a gaseous or vaporous medium whereby it is carried along with the vapors through the reaction chamber.

The products of the catalytic cracking pass to a separating and fractionating chamber 50 wherein the products are subjected to a primary separation and dephlegmation. Uncondensed vapors pass to a secondary fractionating tower 51 wherein a further fractionation occurs to separate reflux condensate from uncondensed vapors. The latter vapors pass to a condenser coil 52 thence to a receiving drum or gas separator 53 wherein the gasoline or naphtha distillate is collected.

In practicing the invention a crude oil charging stock is heated to a desired distilling temperature and separated into vapors and residue in the fractionator 12. The crude oil residue is withdrawn from the tower through a line 54 and directed by a pump 55 through a line 56 to the dephlegmating tower 50 to dephlegmorate the vapors therein received from the catalytic cracking operation. The resultant mixture of residual constituents and reflux condensate comprising the higher boiling products from the catalytic cracking operation and unvaporized constituents of the crude residue is withdrawn from the tower 50 by a pump 57 and directed through a line 58 to the heating coil 19 wherein the oil is subjected to cracking temperature under superatmospheric pressure. The vapors from the tower 50 are subjected to further fractionation in the sec-

ondary tower 51 to separate intermediate constituents of the nature of gas oil and kerosene from the lower boiling motor fuel distillate. The intermediate condensate is withdrawn from the tower 51 by a pump 59 and directed through a line 60 to the heating coil 17 wherein the oil is subjected to cracking temperature under superatmospheric pressure. The condensate stock is subjected to higher cracking temperatures or to higher rates of cracking per pass in the coil 17 than are applied to the residual or higher boiling stock being subjected to cracking in the coil 19. The effluent from the two heating coils is combined for further thermal cracking in the reaction chambers 23, 24 and 25 and the products separated into vapors and residue in the latter reaction chamber. The separated vapors pass to the fractionators 27 and 29 wherein the vapors are fractionated under superatmospheric pressure. The residue, together with a sufficient portion of the vapors to accomplish coking, is passed to the coking drum 40 maintained under reduced pressure wherein conversion to coke is accomplished by contained heat. The higher boiling reflux condensate which is separated in the pressure fractionating tower 27 passes through a line 61 and a pressure-reducing valve 62 to the dephlegmating section 42A to dephlegmorate the coke still vapors therein. Reflux condensate from the secondary pressure fractionator 29 is passed through a line 63 and pressure-reducing valve 64 and is directed either through branch-line 65 to the dephlegmator 42A or through branch-line 66 to the dephlegmator 42B. Straight-run condensate of the nature of gas oil or kerosene is withdrawn from the tray 13 of the crude stripping tower 12 and is directed by a pump 67 through a line 68 to the tower 42 or to the section 42B thereof to reflux the vapors therein. In this way intermediate constituents of the nature of gas oil or kerosene comprising straight-run constituents and constituents from the thermal cracking and coking operations are combined in the reflux condensate collecting in tray 43. This condensate is withdrawn through a line 69 and is directed by a pump 70 through the line 71 to the heating coil 47 and constitutes the charge to the catalytic cracking step.

From the preceding description it will be seen that the charging stock for the catalytic cracking step consists of a mixture of straight-run stock and thermally cracked stock of intermediate boiling range and that the charge to the thermal cracking step consists of the higher boiling or residual component of the crude oil and the higher boiling as well as intermediate boiling products of the catalytic cracking step. Furthermore, it will be seen that there is no recycling within either the thermal or catalytic cracking stage. In other words, the charge for the catalytic cracking operation is passed once through the catalytic cracking zone and the higher boiling or insufficiently converted constituents are directed to the thermal cracking zone and likewise the charge for the thermal cracking zone is passed once through the thermal cracking zone and intermediate boiling range products recovered from the thermal cracking are directed to the catalytic cracking zone.

* In the processing of crudes containing gasoline of relatively low anti-knock quality it may be desirable to subject such gasoline to reforming. For this purpose a pump 72 withdraws a heavy naphtha fraction from the tray 14 through a line 73 and directs it through a line 74 to the

heating coil 32. In case it is desired to subject the entire gasoline fraction to reforming the distillate from receiver 46 may be conducted through a line 78 thence through line 73, pump 72 and line 74 to the heating coil 32. When reforming only the heavy gasoline or naphtha fraction, the light fraction may be withdrawn through a line 76.

The gasoline product obtained in the flash-coking operation will ordinarily be of lower anti-knock quality than that of the gasoline obtained by either the thermal cracking or catalytic cracking. For the purpose of reforming this gasoline, which ordinarily need be applied only to the higher boiling constituents thereof, heavy naphtha condensate which collects in the tray 44 of the tower 42 is withdrawn through a line 77 and directed by a pump 78 through a line 79 to the heating coil 34 wherein it is subjected to reforming. For the purpose of reforming gasoline constituents from the thermal cracking operation a trapout tray 80 may be provided in the pressure fractionator 29 in which a heavy naphtha fraction may be collected. This fraction may be passed through a line 81 and pressure-reducing valve 82 to the fractionating section 42C. Due to the relatively high pressure in the tower 29 the fraction withdrawn from tray 80 will contain light fractions which are vaporized in the low pressure fractionator 42C and are consequently recovered in the distillate collected in the receiver 46. In this manner a maximum gasoline yield is obtained when improving the volatility and octane number.

In an alternative method of operation the cracked residue separated in the reaction chamber 25 instead of being subjected to coking is passed through a branch-line 83 and combined with the separated vapors passed to the fractionator 27. The resultant residue and reflux condensate collected in tower 27 is then passed through pressure-reducing valve 62 and line 61 to the dephlegmating section 42A wherein it is subjected to flash distillation. The flashed residue is withdrawn through a line 84. When the coking drum 40 is used the dephlegmator produced in the dephlegmator 42A and withdrawn through line 84 consists essentially of high boiling constituents produced in the coking operation. This product is of a highly aromatic character and is well adapted for fuel oil blending.

In practicing the invention the catalytic cracking operation is conducted under relatively low pressures such as from about 100 p. s. i. down to atmospheric pressure, while the thermal cracking operation in the reaction chambers is conducted under higher pressures preferably over 200 p. s. i. The pressure in the fractionator of the thermal cracking system is maintained relatively high. It is advantageous to maintain a sufficiently high pressure in the reaction chambers as to have pressures of 400 p. s. i. or higher in the fractionator 29 and gas separator 31, particularly when it is desired to recover normally gaseous constituents for recycling in the system. Under such pressures the gases separated in receiving drum 31 consist predominantly of hydrogen, methane and C₂ hydrocarbons and the gasoline product collected in the receiver 31 may be debutanized to obtain a normally gaseous fraction comprising C₃C₄ hydrocarbons which may be recycled to any of the cracking or reforming coils for gas reversion with the normally liquid hydrocarbons undergoing cracking or reforming.

In an example of invention a crude oil charg-

ing stock is heated to a distillate temperature of 670° F. and fractionated in the tower 12 to obtain a gas oil fraction of 800° F. end point, heavy naphtha of 450° F. end point and light naphtha of 300° F. end point. The straight-run gas oil is refluxed in the fractionator 42B, while the reduced crude is refluxed in the fractionator 50. A gas oil fraction consisting of straight-run constituents and constituents produced in thermal cracking and coking is withdrawn from tray 43 and after heating in the coil 47 to 1000° F. is contacted with a synthetic silica-alumina catalyst in the chamber 49 under a pressure of 50 p. s. i. The catalytically cracked products are directed at a temperature of 950° F. to the tower 50. Unvaporized crude residuum and higher boiling constituents of the catalytic cracking are withdrawn from tower 50 at a temperature of 750° F. and subjected to cracking in the coil 19 at a temperature of 930° F. The vapors from the tower 50 are subjected to further fractionation in the tower 51 to separate higher boiling reflux condensate from the catalytic gasoline. The reflux condensate is withdrawn from the tower at a temperature of 580° F. and is subjected to cracking in the coil 17 at a temperature of 930° F. The effluent from coils 17 and 19 is combined and subjected to further thermal cracking in the reaction chambers under a pressure of 500 p. s. i. with a temperature of 900° F. in the final reaction chamber 25. The bottoms from reaction chamber 25, together with a minor portion of the vapors sufficient to support autogenous coking, are expanded into the coking drum wherein coking is accomplished under a pressure of 40 p. s. i. The straight-run heavy naphtha fraction is subjected to reforming in the coil 32 at a temperature of 1000° F. under 1200 p. s. i. and the products discharged into the primary dephlegmator 21. This dephlegmator is maintained at 450 p. s. i. and the bottoms are withdrawn at a temperature of 850° F. and refluxed in the lower pressure dephlegmator 42A. The tower 29 is maintained at a pressure of 430 p. s. i. and reflux condensate is withdrawn therefrom at a temperature of 780° F. and refluxed in the dephlegmator 42A. Heavy condensate constituting a synthetic fuel oil is withdrawn from dephlegmator 42A at a temperature of 800° F. A heavy naphtha fraction consisting predominantly of gasoline fractions produced in the coking is withdrawn from tray 44 and, after being subjected to thermal reforming in the coil 34 at a temperature of 1000° F. and under a pressure of 1200 p. s. i. is directed to fractionating tower 27. The light coke still gasoline is collected in the receiver 46 and the thermally cracked gasoline is collected in receiver 31.

In another example of the invention the process is conducted in a manner similar to that of the preceding example except that the coking operation is omitted and the residue from the reaction chamber 25 is combined with the reflux condensate formed in the fractionator 21 and flashed in the dephlegmator 42A from which a fuel oil product is withdrawn through the line 84. The coke still gasoline collected in receiver 46 may, with advantage, be refluxed on the pressure tower 29 so that the total gasoline product from the thermal cracking and flashing or coking operation may be collected in the receiver 31. This procedure is advantageous when it is desired to subsequently debutanize the gasoline product so as to obtain C₃C₄ fractions for recycling to any of the cracking or reforming coils.

While I have described a particular embodiment of my invention for purposes of illustration, it should be understood that various modifications and adaptations thereof which will be obvious to one skilled in the art, may be made within the spirit of the invention as set forth in the appended claims.

I claim:

1. In a combination thermal and catalytic cracking process the method that comprises fractionating crude petroleum to obtain a residual fraction and a condensate fraction, subjecting oil to catalytic cracking in a catalytic cracking zone, directing the resultant products of the catalytic cracking to a dephlegmating zone, dephlegmating the vapors therein with said residual fraction, passing unvaporized constituents from said dephlegmating zone through a heating zone wherein the oil is subjected to cracking temperature, subjecting the dephlegmated vapors from said dephlegmating zone to further fractionation to separate higher boiling fractions from lower boiling fractions, passing said higher boiling fractions through a heating zone wherein the oil is subjected to cracking temperature, combining the effluent from said heating zones for thermal cracking in a reaction zone maintained under superatmospheric pressure and wherein separation of vapors from liquid residue takes place, fractionating the separated vapors under superatmospheric pressure to separate reflux condensate from lighter fractions, directing said liquid residue into a lower pressure flashing zone wherein vapors separate from residue, passing the separated vapors to a separate dephlegmating zone, directing reflux condensate, obtained in the fractionation of the vapors from the thermal cracking operation, and condensate, obtained from the crude oil fractionation, to the latter dephlegmating zone to dephlegmate the flashed vapors therein and subjecting the commingled constituents to fractionation to obtain a fraction containing flashed constituents as well as constituents from the crude oil fractionation and thermal cracking, and directing said fraction to the aforesaid catalytic cracking zone.

2. In a combination thermal and catalytic cracking process the method that comprises fractionating crude petroleum to obtain a residual fraction and a condensate fraction, subjecting oil to catalytic cracking in a catalytic cracking zone, directing the resultant products of the catalytic cracking into a dephlegmating zone, dephlegmating the vapors therein with said residual fraction, passing unvaporized constituents from said dephlegmating zone through a heating zone wherein the oil is subjected to cracking temperature, subjecting the dephlegmated vapors from said dephlegmating zone to further fractionation to separate higher boiling fractions from lower boiling fractions, passing said higher boiling fractions through a heating zone wherein the oil is subjected to cracking temperature, combining the effluent from said heating zones for thermal cracking in a reaction zone maintained under superatmospheric pressure and wherein separation of the vapors from liquid residue takes place, fractionating the separated vapors under superatmospheric pressure to separate reflux condensate from lighter fractions, directing said liquid residue to a coking zone wherein it is converted to coke, passing evolved vapors from the coking zone to a separate dephlegmating zone, introducing reflux condensate, obtained in fractionating the vapors from the

thermal cracking operation, and condensate, obtained in the crude petroleum fractionation, to the latter dephlegmating zone to dephlegmate the vapors therein and subjecting the commingled constituents to fractionation to produce a fraction containing constituents from the coking operation and from the crude petroleum fractionation and thermal cracking and directing said fraction to the catalytic cracking zone.

3. In a combination thermal and catalytic cracking process the method that comprises fractionating crude petroleum to obtain a gas oil fraction and a residual oil fraction, subjecting oil to catalytic cracking in a catalytic cracking zone, directing the resultant products of the catalytic cracking to a dephlegmating zone, introducing said residual fraction to said dephlegmating zone to dephlegmate the vapors therein, withdrawing a residual fraction from said dephlegmating zone and passing said fraction through a heating zone wherein it is subjected to cracking temperature, subjecting vapors uncondensed in said dephlegmating zone to further fractionation to separate a gas oil fraction from lighter constituents, passing said gas oil fraction through a heating zone wherein it is subjected to cracking temperature, combining the effluent from said heating zones for thermal cracking in a reaction zone maintained under superatmospheric pressure and wherein separation of vapors from liquid residue takes place, fractionating the separated vapors to obtain a gas oil fraction, flash-distilling said liquid residue to obtain a gas oil fraction, combining gas oil constituents obtained in the fractionation of the crude petroleum with gas oil constituents from the thermal cracking and coking operations and directing the resultant composite gas oil fraction to said catalytic cracking zone.
4. In a combination thermal and catalytic cracking process the method that comprises fractionating crude petroleum to obtain a residual fraction and a condensate fraction, subjecting oil to catalytic cracking in a catalytic cracking zone, directing the resultant products of the catalytic cracking into a dephlegmating zone, dephlegmating the vapors therein with said residual fraction, passing unvaporized constituents from said dephlegmating zone through a heating zone wherein the oil is subjected to cracking temperature, subjecting the dephlegmated vapors from said dephlegmating zone to further fractionation to separate higher boiling fractions from lower boiling fractions, passing said higher boiling fractions through a heating zone wherein the oil is subjected to cracking temperature, combining the effluent from said heating zones for thermal cracking in a reaction zone maintained under superatmospheric pressure and wherein separation of the vapors from liquid residue takes place, fractionating the separated vapors under superatmospheric pressure to separate reflux condensate from lighter fractions, directing said liquid residue to a coking zone wherein it is converted to coke, passing evolved vapors from the coking zone to a separate dephlegmating zone, introducing reflux condensate, obtained in fractionating the vapors from the thermal cracking operation, and condensate, obtained in the crude petroleum fractionation, to the latter dephlegmating zone to dephlegmate the vapors therein and subjecting the commingled constituents to fractionation to separate a naphtha fraction from higher boiling reflux condensate containing constituents from the

coking operation and from the crude petroleum fractionation and thermal cracking, directing the latter higher boiling reflux condensate to the catalytic cracking zone, passing said naphtha fraction through a reforming zone wherein the naphtha is subjected to a reforming temperature to raise the anti-knock quality thereof and fractionating resultant products of the reforming with vapors from the aforesaid thermal cracking.

5. In a combination thermal and catalytic cracking process the method that comprises fractionating crude petroleum to obtain a residual fraction, a gas oil fraction and a naphtha fraction, subjecting oil to catalytic cracking in a catalytic cracking zone, directing the resultant products of the catalytic cracking to a dephlegmating zone, dephlegmating the vapors therein with said residual fraction, passing unvaporized constituents from said dephlegmating zone through a heating zone wherein oil is subjected to cracking temperature, subjecting the dephlegmated vapors from said dephlegmating zone to further fractionation to separate higher boiling fractions from lower boiling fractions, passing said higher boiling fractions through a heating zone wherein the oil is subjected to cracking temperature, combining the effluent from said heating zones for thermal cracking in a reaction zone maintained under superatmospheric pressure and wherein separation of vapors from liquid residue takes place, fractionating the separated vapors under superatmospheric pressure to separate reflux condensate from lighter fractions, directing said liquid residue into a lower pressure flashing zone wherein vapors separate from residue, passing the separated vapors to a separate dephlegmating zone, directing reflux condensate, obtained in the fractionation of the vapors from the thermal cracking operation, and condensate, obtained from the crude oil fractionation, to the latter dephlegmating zone to dephlegmate the flashed vapors therein and subjecting the commingled constituents to fractionation to obtain a fraction containing flashed constituents as well as constituents from the crude oil fractionation and thermal cracking, directing said fraction to the aforesaid catalytic cracking zone, passing the naphtha fraction from the crude petroleum through a thermal reforming zone wherein the naphtha is subjected to a

reforming temperature to raise the anti-knock quality thereof and fractionating the resultant reformed products with vapors from the aforesaid thermal cracking.

6. In a combination thermal and catalytic cracking process the method that comprises fractionating crude petroleum to obtain a residual fraction, a gas oil fraction and a naphtha fraction, subjecting oil to catalytic cracking in a catalytic cracking zone, directing the resultant products of the catalytic cracking into a dephlegmating zone, dephlegmating the vapors therein with said residual fraction, passing unvaporized constituents from said dephlegmating zone through a heating zone wherein the oil is subjected to cracking temperature, subjecting the dephlegmated vapors from said dephlegmating zone to further fractionations to separate higher boiling fractions from lower boiling fractions, passing said higher boiling fractions through a heating zone wherein the oil is subjected to cracking temperature, combining the effluent from said heating zones for thermal cracking in a reaction zone maintained under superatmospheric pressure and wherein separation of the vapors from liquid residue takes place, fractionating the separated vapors under superatmospheric pressure to separate reflux condensate from lighter fractions, directing said liquid residue to a coking zone wherein it is converted to coke, passing evolved vapors from the coking zone to a separate dephlegmating zone, introducing reflux condensate, obtained in fractionating the vapors from the thermal cracking operation, and condensate, obtained in the crude petroleum fractionation, to the latter dephlegmating zone to dephlegmate the vapors therein and subjecting the commingled constituents to fractionation to separate a naphtha fraction from higher boiling reflux condensate containing constituents from the coking operation and from the crude petroleum fractionation and thermal cracking, directing the latter higher boiling reflux condensate to the catalytic cracking zone, passing the aforesaid naphtha fractions through a reforming zone wherein the naphtha is subjected to a reforming temperature to raise the anti-knock quality thereof and fractionating resultant products of the reforming with vapors from the aforesaid thermal cracking.

RICHARD F. TROW.
